UNITED STATES PATENT OFFICE.

ROBERT C. GREENHALGH, OF PHILADELPHIA, PENNSYLVANIA.

MACHINE FOR CUTTING DOUBLE-PILE FABRICS.

SPECIFICATION forming part of Letters Patent No. 323,667, dated August 4, 1885.

Application filed November 24, 1884. (No model.)

To all whom it may concern:

Be it known that I, ROBERT C. GREENHALGH, a citizen of the United States, and a resident of Philadelphia, Pennsylvania, have 5 invented certain Improvements in Machines for Cutting Double-Pile Fabrics, of which the following is a specification.

The object of my invention is to so construct a machine for severing double-pile fabrics as 10 to insure an even pile on each of the severed strips, a further object being to provide steady bearings for the rapidly-revolving cutting-knives, and to permit the adjustment of the latter.

15 In the accompanying drawings, Figure 1, Sheet 1, is a longitudinal section of my improved machine for cutting double-pile fabrics; Fig. 2, Sheet 2, a plan view of the same, without counter-shaft and driving-belts; Fig. 20 3, Sheet 3, a transverse section on the line 1 2, Fig. 1; and Fig. 4, Sheet 1, an enlarged section of part of the machine.

A is the frame of the machine, to suitable bearings in which are adapted the shafts of 25 the drums B B and the spindles of a series of guide-rollers, a, and at the top of the frame are the transverse bars D D', the space between which is such as to permit the passage of the double-pile fabric x, which is severed by 30 the knives F, the severed pile-strips y being drawn one over one bar, D, and the other over the opposite bar, D'. The spindles of the knives F are adapted to bearings on a slide, G, which is guided on a transverse bar, H, of 35 the frame, and is reciprocated laterally by means of a crank-wheel, b, on a shaft, I, adapted to bearings in brackets at the side of the machine, the crank-pin of the wheel being connected by a rod, b', to a stud on the slide G. 40 The shaft I has a pulley, d, for receiving the driving-belt, and another pulley, d', the belt d' from which passes round a pulley, e, on a shaft, J, adapted to bearings e' on the frame, said shaft J having a worm, f, which gears into 45 a worm-wheel, f', on a sleeve, g, the latter turning on a stud, g', on the frame and having a pinion, h, gearing into a spur-wheel, i, on the shaft of one of the drums B, the other drum having a similar spur-wheel, i', gearing into 50 the wheel i, so that said drums are caused to rotate in opposite directions.

So far as described the machine is substantially similar to others which have been devised, except that the gearing is considerably simplified. In the ordinary machines, however, it is the practice to pass the strips y from the bars D D' directly around the drums B B, which are covered with sand-paper or other rough material, so as to serve as drawing-drums. In the event of any defect in the draft 60 of either of the drums the strip y controlled thereby is subjected to less tension than the opposite strip; hence the double-strip x is not held exactly central in respect to the cutting-knives, and the latter are liable to cut closer 65 to one strip y than to the other, so that there is a resulting unevenness in the length of the pile. To overcome this defect I use opposite rollers M, the bearings of which are in boxes 70 m, free to slide on guides n on the side frames, and connected to pendent weights p by cords p' passing over suitable pulleys, p'. The cut strips y pass around the rollers M before reaching the drums B, so that there is a definite and uniform tension at all times on each 75 of the strips, and irregular cutting of the pile is effectively obviated.

The mode of hanging the cutter-spindles is shown in Fig. 4, in which t represents one of the spindles, squared or otherwise, formed at 80 one end for the reception of the cutter F and at the opposite end for the pulley w, said cutter and pulley being secured by nuts w', as usual. The spindle has its bearing in a sleeve, 85 P, which is adapted to a vertical slot, k, in the slide G, a collar, S, on the sleeve bearing against the face of the slide, and a nut, T, adapted to the threaded portion of the sleeve, bearing against the inner side of the slide, so that as the cutter becomes worn and is reduced in 90 diameter the sleeve can be adjusted so as to compensate for this reduction and preserve the cutter in proper working position. When there is a change in the size of the cutter, the bar H is adjusted vertically, and in order to 95 permit this said bar is secured to the standards H' by means of bolts z, adapted to vertical slots z' in the bar, as shown in Fig. 3. There are in the present instance three cutters, the spindles of which are driven by means 100 of a belt, g, adapted to the pulleys w of the cutter-spindles and to a pulley, w', on a

counter shaft, K, the latter being driven from the shaft I through the medium of a belt, u, adapted to a pulley, v, on said shaft I, and to a pulley, v', on the counter-shaft. The pulley 5 w' is directly over the center of the slide G when the latter is in the mid-position, as shown in Fig. 3, so that the slide can be reciprocated within the required limits without loosening the belt, the slack formed by the decrease of angle of the belt on one side being taken up by the increase of angle on the opposite side.

Instead of subjecting the bearings of the rollers M to the action of suspended weights, 15 springs may be used, as shown, for instance, by dotted lines in Fig. 1, and plain rods, bars, or strips may be used with the tension-regulating devices instead of the rollers shown, although the latter are preferred.

20 I claim as my invention—

1. The combination of the bearing-bars D D', the drawing-drums B B, the pile-cutters, mechanism for actuating said drums and cutters, tension bars or rollers M, and means for 25 causing said bars or rollers to bear upon the cut strips before the latter reach the drawing-drums, all substantially as set forth.

2. The combination of the bearing-bars D D', the drawing-drums B B, the pile-cutters, a slide carrying the spindles of said cutters, 30 mechanism for rotating the drums and cutters and reciprocating the slide, tension bars or rollers M, and means for causing said bars or rollers to bear upon the cut strips before the latter reach the drawing-drums, all substantially as specified. 35

3. The combination of the slide carrying a series of spindles, each having a belt-pulley and cutter, mechanism for reciprocating the slide, a counter-shaft located above and centrally within the limits of reciprocation of said slide, a pulley, w', on said counter-shaft, and a belt, q, adapted to said pulley w' and to the pulleys of the cutter-spindles, as set forth.

In testimony whereof I have signed my 40 name to this specification in the presence of two subscribing witnesses.

ROBERT C. GREENHALGH.
